Whittier & Wright,

UNITED STATES PATENT OFFICE.

EDWARD ZWIEBEL, OF POTTSVILLE, PENNSYLVANIA.

HYDRANT.

SPECIFICATION forming part of Letters Patent No. 397,213, dated February 5, 1889.

Application filed June 15, 1888. Serial No. 277,171. (No model.)

To all whom it may concern:

Be it known that I, EDWARD ZWIEBEL, a citizen of the United States, residing at Pottsville, in the county of Schuylkill and State of Pennsylvania, have invented certain new and useful Improvements in Hydrants; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to hydrants; and its object is to enable the discharge-nozzle to be faced in any direction independent of the point of attachment of the supply-pipe.

A further object is to render the parts easy to construct, assemble, and repair, and readily accessible, when necessary.

In the drawings, Figure 1 is a vertical section, and Fig. 2 an elevation, of my improved hydrant.

The body A is cylindrical or slightly tapering, and is closed at the bottom by a plate, B, bolted or otherwise secured to it. The supply-pipe C enters through the side of the body A, near the bottom, and communicates with a chamber formed in a block, D, which is located at the center of the plate B, where it is secured by a threaded stud, d, projecting downwardly through the plate, and provided with a nut, D', underneath the plate.

The upper face of the block D is flat, and in it is formed a cylindrical opening, d', concentric with the axis of the body A and communicating with the chamber within the block. In this opening is mounted the valve-

casing E, the interior of which is cylindrical. Its lower end is closed by a tubular screw-plug, F, which has a flange, f, seated against the end of the valve-casing, and a neck, f', fitting into the opening d', which thus forms a bearing in which the valve-casing can be rotated. A suitable gasket, G, is interposed between the flange f and the upper face of the block D, to make a water-tight joint between the block and the valve-casing.

On the upper end of the valve-casing is an internally-threaded neck, e, in which works the threaded valve-stem H. A packed screw-

cap, e', prevents any escape of water around the valve-stem. At one side of the valve-casing and communicating therewith is an elbow, E', into the top of which is inserted the discharge-pipe K. The valve consists of two pistons, h h', attached to the stem H and held apart by a spring, I, between them. The distance between them and the tension of the spring I can be regulated by adjusting the piston h' up or down on the stem. When the valve is moved downward, the packing h² on the piston h' seats upon the upper end of the plug F and closes the passage through which the water enters the valve-casing, while the piston h opens communication between the elbow E' and the upper part of the valve-casing, allowing any water in the discharge-pipe K to escape through a small opening, k, in the top of the valve-casing and a hole, b, in the bottom plate, B. When the valve is lifted, the opening k is closed by the piston h, while the piston h' opens communication between the supply-pipe C and the discharge-pipe K through the elbow E'.

The body A is surmounted by a cap, A', which is held in any desired position by means of a set-screw, L. Through the center of the cap passes the spindle H', which engages with a socket in the upper end of the valve-stem H. The spindle, the valve-stem, and the tubular plug F are all arranged in the axial line of the hydrant-body A.

On the under side of the cap A' and in line with the discharge-pipe K is a socket, a, into which fits the upper end of a T-shaped piece, M, the stem M' of which projects through the side of the cap A'. The lower end of the piece M receives the upper end of the discharge-pipe K, and an elbow-shaped passage, m, is formed through the piece M from the pipe K to the end of the stem M', where the nozzle A² is attached.

Surrounding the body A, just below the cap A', is an undercut flange, a², with which engage two or more hooked bolts, N, whose upper ends pass through lugs a' on the cap A', where they are secured by nuts n. By tightening the nuts the cap is drawn downward over the body A, carrying with it the pipe K and valve-casing E, and forcing the flange f down upon the gasket G.

This hydrant can be set up and connected

with the service-pipe independent of the direction in which the nozzle is to face, since the cap A' can be revolved to any position upon loosening the bolts N, the valve-easing 5 rotating upon its seat in the block D.

Having thus described my invention, what I claim, and desire to secure by Letters Patent, is—

1. The combination, with a hydrant-body 10 having a supply-pipe and a centrally-arranged block containing a chamber communicating with the supply-pipe, of a valve-easing provided with a tubular plug fitting into the block and communicating with the chamber, 15 a valve seating upon the upper end of the plug, a discharge pipe and nozzle, a rotatable

and vertically-movable cap bearing upon the upper end of the discharge-pipe, and means for drawing the cap downward over the hydrant-body, substantially as described. 20

2. The combination, with the body A, rotatable cap A', valve-easing E, and discharge-pipe K, of the T-shaped piece M, inserted between the upper end of the pipe K and the under side of the cap A' and provided with a 25 passage, m, substantially as described.

In testimony whereof I affix my signature in presence of two witnesses.

EDWARD ZWIEBEL.
